SIGNORS TO LANDERS, FRARY & CLARK, OF NEW BRITAIN, CONNECTICUT, A COR-
PORATION OF CONNECTICUT

SAFETY DEVICE FOR CENTRIFUGAL DRIERS

Application filed May 29, 1928. Serial No. 281,451.

This invention relates generally to centrifugal driers, such as machines for drying laundry, of the type having a rotating basket or receptacle and a cover over the open end of the receptacle.

The present invention relates more particularly to a safety device for preventing the power from being thrown onto the basket when the cover is in open condition, and for preventing the cover from being opened while the basket is being driven. Thus, injury to the person or persons operating the machine is effectively guarded against, a feature of considerable importance as not infrequently machines of this type are operated by inexperienced persons knowing little or nothing about machinery.

The aim of the invention is to provide an improved safety device of this sort which is very simple in construction, which is very effective in operation, and which may be easily and quickly operated.

Other objects will be in part obvious and in part pointed out hereinafter more in detail.

The invention accordingly consists in the features of construction, combination of elements and arrangement of parts which will be exemplified in the construction hereinafter set forth and the scope of the application of which will be indicated in the appended claims.

In the accompanying drawings, wherein we have shown, for illustrative purposes, one of the embodiments which the present invention may take:

Figure 1 is a vertical central view through the upper end of a centrifugal extractor, this view being taken substantially on line 1—1 of Fig. 2 and showing the cover in closed and locked condition;

Fig. 2 is a top plan view showing the safety device in locking condition, so much of the extractor being illustrated as will make one application of the invention clear;

Fig. 3 is a view similar to Fig. 2, but showing the safety mechanism in unlocked condition;

Fig. 4 is a side elevational view of the safety mechanism in locked condition, as shown in Fig. 2; and

Fig. 5 is a detail view taken substantially on line 5—5 of Fig. 2.

Referring to the drawings in detail, the centrifugal extractor therein shown is disclosed by way of illustration and more or less diagrammatically, as the specific construction thereof may be varied as desired. The basket or receptacle of this extractor may be driven in any suitable manner, the driving mechanism not being illustrated, as machines of this type are old and well-known. In these drawings, the letter A designates the rotatable receptacle which, in the present instance, is in the form of an imperforate basket having, adjacent its upper end, openings 10 through which the water is adapted to be discharged into an annular channel or reservoir 11 located in a drain board or frame B. About the centrifugal receptacle A is a casing or shell C. Pivoted to the drain board, as at 12, is a cover D adapted, when closed, to rest upon an annular seat 13. The letter E designates a lid rotatably carried by the cover D and adapted to fit into and rest on the top of the receptacle A, as is usual in centrifugal driers of this sort.

The numeral 20 designates a control lever for controlling the mechanism through which the centrifugal receptacle A is driven. This lever 20 is fixed to the upper end of a pin or stud 21 journalled in the drain board and carrying, on its lower end, a cam plate 22 which is adapted to be connected by a rod or other suitable arrangement to the driving mechanism, the rod not being shown. It is evident that the connection between the member 22 and the driving mechanism may be of any suitable sort; for example, in the event that the receptacle A is driven through a clutch having a shiftable sleeve, the member 22 will be associated with the sleeve in such manner that, when the lever 20 is in the position shown in Figs. 1 and 2, the sleeve is engaged so that the receptacle is driven.

When the lever 20 is in the position shown in Fig. 3, the clutch is disengaged so that the power is thrown off of the receptacle A. It may further be mentioned that, as is usual in machines of this sort, a brake (not shown)

is provided for quickly stopping the receptacle when the power is thrown off.

Journalled in the drain board along side of the stud 21 is a stud 25 to the upper end of which is fixed a cover locking member 26. The cover D may be provided with a locking or strike plate 27. The locking member 26, when in locking position, as shown in Figs. 1 and 2, is adapted to overlie the plate 27. 10 The corner 28 of the strike plate and the forward edge 29 of the locking member 26 are preferably round so that the locking member may ride onto the strike plate and clamp the cover securely to its seat. On the lower 15 end of the stud 25 is a handle or lever 30 for turning the stud together with the locking member 26 carried thereby. The control lever 20 has a cam 35 adapted to engage the locking member 26 and move the same to locking position when the control lever 20 is moved in a direction to throw the power onto the centrifugal receptacle A.

Mounted on the stud 25 for turning movement relative thereto is a lever 36 which is 20 controlled by the cover D and which serves to automatically lock the control lever 20 against actuation when the cover is open. One end 37 of this lock or lever 36 is adapted to cooperate with an abutment or tooth 38 on 25 the control lever when the cover is open, as shown in Fig. 3. The other end of the control lever lock 36 has an inclined or cam surface 39 which is in the plane of the edge of the cover D when the cover is closed. When 30 the cover is closed, the edge thereof engages the lever 36 so that the latter is held out of locking position.

When the cover is thrown open, the control lever lock 36 is automatically thrown 40 into locking position by a spring 40, one end of which is secured, as by means of a rivet 41, to the lock 36, and the other end 42 of which is fixed to the bearing through which the stud 25 extends.

45 The operation of the safety device is briefly as follows: Assuming that the machine has been operating with the parts in the position shown in Figs. 1 and 2, and the wringing operation has been completed, the control lever 20 is turned clockwise from the 50 position shown in Fig. 2 to that shown in Fig. 3 so as to throw the power off of the basket A. When the control lever is thus thrown, the cam 35 is moved out of the path 55 of movement of the cover lock 26. The lever or handle 30 may then be turned from the position shown in Fig. 2 to that shown in Fig. 3 so as to withdraw the cover lock from the strike plate 27. The cover may now be 60 raised without danger of injury to the operator as the receptacle has been brought to a stop. When the cover is raised, the edge of the cover is moved out of the path of movement of the end 39 of the control lever lock 36 so that this member 36 may move from

the position shown in Fig. 2 to that shown in Fig. 3. In the latter position, the end or tooth 37 engages the abutment 38 so that the control lever 20 cannot be moved in a direction to throw the power onto the receptacle 70 while the cover is open. The other end 39 of the control lever lock 36 overhangs the seat 13 and is in the path of movement of the free edge of the cover D. Before the power is again thrown onto the receptacle, 75 it is necessary to close the cover for, as stated, while the cover is open, the lock 36 secures the control lever 20 against operation.

When the cover D is closed, the edge thereof engages the cam surface 39, thereby camming the lock 36 to the position shown in Fig. 2 so that the end 37 is moved out of the path of movement of the abutment 38. Then the control lever may be operated to throw the power onto the receptacle A. When the control lever is thus operated, the cam 35 thereon pushes the cover lock 26 over the strike plate 27, thus locking the cover down.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

We claim as our invention:

1. In a centrifugal drier, a rotatable receptacle, a cover therefor, a control lever for said receptacle, a cover locking member, means on said control lever for preventing actuation of said locking member when said lever is in operated position, a control lever lock adapted to lock said lever against actuation when the cover is open, said control lever lock having a portion adapted to lie in the path of movement of the cover when the cover is open and to be cammed outwardly when the cover is brought to closed position, and means for normally urging said lock to locking position.

2. In a centrifugal drier, a rotatable receptacle, a cover therefor, a control lever for said receptacle, a cover locking member, means on said control lever for preventing actuation of said locking member when said lever is in operated position, said control lever having an abutment, a pivoted lock, one end of which is adapted to engage said abutment and the other end of which is adapted to be engaged by said cover, and a spring normally urging said lock to locking position.

3. In a centrifugal drier, a rotatable receptacle, a cover therefor, a control lever for said receptacle and having an abutment, a locking lever adapted to be moved to and from position over the edge of said cover, a cam on said control lever adapted to cam and hold said cover locking member in locking position when said control lever is in operated position, a pivoted control lever lock having a portion adapted to engage said abutment to prevent actuation of said control lever when the cover is open, said lock having a cam portion adapted to lie in the path of movement of said cover when the cover is open and to be cammed outwardly when the cover is closed, and a spring normally urging said lock into locking position.

4. In a centrifugal drier, a rotatable receptacle, a cover therefor, a control lever for said receptacle, a locking member for said cover, means fixed to and movable with said control lever and adapted to directly engage said locking member for preventing actuation of said locking member when said lever is in operated position, and means for preventing the power from being thrown onto said receptacle when said cover is open, said means having a portion lying in the path of movement of the cover when the cover is open and adapted to be cammed outwardly when the cover is brought to closed position.

5. In a centrifugal drier, a rotatable receptacle, a cover therefor, a control lever for said receptacle, a cover locking member pivoted independently of said cover so as not to be movable therewith, said locking member being adapted to engage and overhang the edge of the cover when the cover is closed and the locking member is in locking position, means on said control lever adapted to directly engage said locking member for preventing actuation of said locking member when said lever is in operated position, and means movable independently of said locking member and lever and controlled by said cover for locking said control lever in inoperative position when the cover is open.

6. In a centrifugal drier, a rotatable receptacle, a cover therefor, a control lever for said receptacle, a cover locking member pivoted independently of said cover and having a portion adapted to overhang the edge of the cover to lock the latter in closed position, a cam on said control lever adapted to directly engage said locking member for preventing actuation of the latter when said lever is in actuated position, and a control lever lock adapted to lock said lever against actuation when the cover is open, said control lever lock having a portion adapted to lie in the path of movement of the cover when the cover is open and to be cammed outwardly when the cover is brought to closed position.
